UNITED STATES PATENT OFFICE.

ELBERT O. HASKINS, OF RUTHERFORD, NEW JERSEY.

HEATING-BOILER.

SPECIFICATION forming part of Letters Patent No. 761,479, dated May 31, 1904.

Application filed October 12, 1903. Serial No. 176,620. (No model.)

To all whom it may concern:

Be it known that I, ELBERT O. HASKINS, a citizen of the United States, residing at Rutherford, in the county of Bergen, State of New Jersey, have invented certain new and useful Improvements in Heating-Boilers, of which the following is a specification.

This invention relates to heating-boilers such as are used for producing steam or heating 10 the water for steam or hot-water heating plants.

The object of my invention is to provide a new and improved heater of this kind, which is simple in construction, light, and economical, and presents a large surface to the flame 15 of the fire on the grate.

In the accompanying drawings, in which like letters of reference indicate like parts in all the figures, Figure 1 is a vertical transverse 20 sectional view of one construction of my improved heating-boiler. Fig. 2 is a front view of the same. Fig. 3 is a horizontal sectional view of the line 3 3 of Fig. 1.

This boiler is constructed with a series of 25 vertical hollow cast-iron sections A. In the boiler illustrated there are four of these sections, which sections have sides in contact, the sections being held together by tie-rods B, that pass through sleeves or necks C in the 30 well-known manner at the top and bottom, and the several sections are united with each other at the top and bottom by push-nipples D in the well-known manner. The lower portion 35 of the front of the boiler in which the fire-door E is arranged is composed of a separate water-back F, having the fire-door opening, which water-back rests on the front of the base G, in which the ash-pit door is arranged, and the upper edge of the water-back F supports 40 the bottom parts of the front of the sections A. This water-back is connected at the top and bottom by pipe connections H or equivalent means with the hollow sections A. The boiler rests on a base J of any suitable 45 construction, which forms the ash-pit. The vertical sections A are all alike with the exception, of course, of the two side sections A', which have solid inner and outer walls a' and may be made in any suitable manner. The

interior sections A are cast with a vertical 50 hollow front water-leg and a hollow rear water-leg b, connected at the top by a horizontal portion d, which forms the steam-chamber in case it is used as a steam-boiler. A short distance to the front of each vertical rear leg b 55 a vertical recess e is formed and extends from side to side of each section, which recesses when the sections are secured side by side form the flues f in front of the vertical rear legs b, the lower ends of which flues f are by 60 suitable openings (shown at g in dotted lines, Fig. 1) brought in communication with a smoke-box i, with which the smoke-pipe i' is connected. An intermediate vertical leg k is formed in each section in front of each flue f 65 and is connected with the front leg a of its section l by a series of upwardly-inclined water-legs l, of which there are five in each section, each having a width equal to about one-half width of the section. Two are formed 70 along one side of the section and three along the other side and they are staggered—that is to say, one is on the left side, the next one above on the right side, the next one above on the left side and, so on alternately. 75

It will be seen that by arranging the inclined water-legs in this manner the legs of the several sections form upwardly-inclined rows or steps of water-legs, between which the products of combustion can readily circulate 80 and which are more or less subjected directly to the flames of the fire on the grate. The bottom of the top water-space d is made horizontal, and between it and the uppermost inclined water-legs l an approximately triangular space m is formed, into which the products of combustion pass. Each vertical intermediate water-leg k is provided with an upward extension m', connecting the upper end of the corresponding intermediate leg k 90 with the top space d of the section. These extensions, however, are not the full width of the section, as appears from Fig. 3, but are reduced in width, so as to leave a space o at each side of such extensions, and the openings 95 o of two adjacent sections establish communication between the flues and the space above the uppermost inclined water-legs l. In order

to prevent the flames and products of combustion from passing from the fire-box upward at an inclination to the rear and for the purpose of deflecting them toward the front, the 5 uppermost legs *l* are widened at their rear parts, so as to have the full width of the section, and are only reduced in width to conform with the other water-legs at the front portions, so as to form recesses *n*. The full-width portions 10 of the uppermost water-legs thus form a baffle-plate or deflecting-plate at the bottom of the chamber *m*, and the recesses *n* form openings at the front and top of the boiler, so as to compel the flame and products of combustion 15 to pass from the fire between the inclined water-legs *l* to the front part of the top of the boiler, through the openings formed by the recesses *n*, and into the space *m*. By this arrangement the flame and products of combustion 20 circulate thoroughly around all the inclined water-legs, are deflected against the front water-legs, and in passing from the space *m* through the rear downwardly-extending flues *f* also serve to heat the sections. 25 The water-legs of the rear vertical legs *b* form the circulating-column of water and the intermediate legs *k* the distributing-column, and between them the return-flue *f* is formed, and thus the heat is fully utilized. 30 Having described my invention, what I claim as new, and desire to secure by Letters Patent, is—

1. A heating-boiler constructed with vertical water-sections, each section having a front, intermediate and rear vertical water-leg, the 35 front and intermediate legs of each section being connected by a series of water-legs inclined downward and toward the rear which water-legs have approximately half the width 40 of the section and are arranged alternately at opposite sides of the section one above the other, substantially as set forth.

2. A heating-boiler constructed with vertical water-sections, each section having a front 45 vertical water-leg, an intermediate vertical water-leg and a rear vertical water-leg, the front and intermediate legs being connected by a series of water-legs, inclined from the front 50 downward toward the rear and arranged alternately at opposite sides of the leg, one

above the other vertical flues being formed between the rear and intermediate legs of the sections, substantially as set forth.

3. A heating-boiler constructed with vertical water-sections, each section having a vertical front water-leg, a vertical intermediate water-leg and a vertical rear water-leg, the front and intermediate legs being connected by a series of water-legs inclined from the front downward toward the rear and arranged 55 alternately on opposite sides of the section one above the other, the uppermost inclined leg of each section having the full width of the section with the exception of the front part of said uppermost leg so as to form a 60 baffle-plate and in front of same an opening for the products of combustion, substantially as set forth.

4. A heating-boiler, constructed with a series of vertical sections, each section having 70 a front, intermediate, and rear vertical water-legs, the front and intermediate legs of each section being connected by a series of water-legs inclined downward and toward the rear, and an upward extension, extending from the 75 top of the intermediate leg of each section, to the top part of the section, which extension is of less width than the section so as to form openings for the passage of the products of combustion from above the uppermost inclined water-legs into the flues formed between the rear and intermediate vertical legs, 80 substantially as set forth.

5. A heating-boiler constructed with a series of vertical hollow water-sections having 85 a vertical front leg, a vertical intermediate leg and a vertical rear leg, the lower ends of the intermediate vertical legs resting on a support, a water-back having a fire-door opening, upon the top of which water-back the 90 lower ends of the vertical front water-legs rest, substantially as set forth.

In testimony whereof I have signed my name to this specification, in the presence of two subscribing witnesses, this 19th day of September, 1903.

ELBERT O. HASKINS.
